UNITED STATES PATENT OFFICE

GEORGE C. LEWIS, OF PHILADELPHIA, PENNSYLVANIA

VACUUM CLEANER

Application filed January 22, 1929. Serial No. 334,162.

My invention relates to a novel construction of suction or vacuum cleaner and an attachment therefor, my invention being applicable to any device employing air suction for the removal of dust and dirt from fabrics or other materials, wherein I employ a novel mechanism which will cause the flow of air through the suction nozzle to be interrupted at regular or irregular intervals, thereby causing vibration of the nap of the material being cleaned, similar to the action of a beater or brush but without the injurious effect of mechanical beating, my novel device being shut off at will and being adjustable at any period readily to cause more or less rapid vibration to suit conditions.

While my invention is capable of being carried out by various forms of mechanisms, I have shown herein one form which may be employed, it being understood that various modifications of the same may be employed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings:

Fig. 1 represents a plan view of a suction or vacuum cleaner having my invention applied thereto.

Fig. 2 represents a side elevation of Fig. 1.

Fig. 3 represents a front elevation of Fig. 2.

Fig. 4 represents upon an enlarged scale a plan view of the intermediate casing, with the cover removed.

Fig. 5 represents a vertical section taken upon the line 5—5 of Fig. 4.

Fig. 6 represents a horizontal section taken upon the line 6—6 of Fig. 5.

Fig. 7 represents a perspective view of one of the valvular elements in detachable position showing the short arm passed thereto and the link forming part of the toggle mecha-

nism whereby the valvular element is actuated.

Similar numerals of reference indicate corresponding parts.

In the drawings, the reference numeral 1 designates my novel construction of a vacuum cleaner provided with a fan chamber 2 having rigidly secured to one end thereof the motor housing 3, the opposite or forward end being provided with a collecting nozzle 4 which terminates in a lateral elongated working portion or suction inlet 5. The fan chamber, motor housing and nozzle constitutes a rigid structure comprising a cleaner casing mounted upon the front and rear rollers 6 and 7, and as this construction per se is well known and made in accordance with the U. S. Patent No. 1,507,417 I deem it unnecessary to show or describe these elements in further detail since my novel invention particularly relates to the intermediate casing 8 positioned between the fan chamber 2 and the collecting nozzle 4. The intermediate casing 8 is preferably rectangular in shape and is provided with a bottom wall 9, side walls 10, and an upper wall 11, see Fig. 5. Upon the upper wall 11 there is formed the rear extension or wall 12 and in the front wall 13, as seen in Fig. 5, said walls being provided with the rear ledge or shoulder 14 and the upper ledge 15 and the side ledges or shoulders 16, see Figs. 4 and 5, on which is supported the cover plate 17. The reference numeral 18 designates a valvular element, best seen in Figs. 5, 6, and 7, the same comprising the body portion 19 having the lower stem or pintle 20 which is mounted on the step bearing 21 seen in Fig. 5. The upper stem or pintle 22 is rotatably mounted in the guide opening 23 in the body 11 and has secured thereto one end of the short arm 24 whose other end is pivotally attached at the point 25 to the link 26. There are two valvular elements 19, one on each side of the intermediate casing 8, as will be understood from Figs. 4 and 6, and there are two arms 24 and two links 26, which links converge and have their inner ends pivotally connected at 27 to the core 28 of the solenoid 29. The reference numeral 30 designates a spring having one end connected

to the pivot point 27 and its opposite end connected to a fixed lug 31, as will be understood from Figs. 4 and 5. 32 designates an automatic make and break switch which by means of the wiring indicated at 33 and 34 controls the energizing of the solenoid 29 whereby the core 28 thereof is reciprocated and by reason of the intermediate connections 25 and 24 the valvular elements 19 are caused to flutter or oscillate within the intermediate casing 8. The latter is provided with the rear flange 36 having connection with the fan chamber 2 while the front flange 37 permits connection to be readily made with the suction nozzle 4. 15 The wiring connection 33 and 34 can be connected to any suitable source of electrical energy as the circuit for the motor within casing 3.

The operation is as follows:
20 When the switch 32 is turned on the solenoid 29 is energized and de-energized, alternately and continuously so long as the switch 32 is turned on and thus causes the core 28 to reciprocate. The reciprocations of the 25 core 28 by reason of the toggle connection, seen in Fig. 4, will cause the valvular elements 19 to flutter or oscillate, the tension of the spring 30 causing said valvular elements normally to assume the position seen 30 in Figs. 4 and 6, which is the position the parts assume when the switch 32 is off. During an operating period, at regular or irregular intervals, as desired, vibration of the nap of the material being cleaned occurs, 35 which vibration is similar to the action of a beater or a brush but without the injurious effects obtained in mechanical beating. In other words, the entire operation of cleaning surfaces according to my novel structure is 40 that of suction. The parts of the intermediate casing 8 are so fitted with respect to one another and with respect to the suction nozzle 4 and fan casing 2 that access may be readily had to the parts operating the valvular elements, the advantage of which is 45 important.

I am aware that the invention may be embodied in other specific forms without departing from the spirit or essential attributes 50 thereof, and I therefore desire the present embodiment to be considered in all respects as illustrative and not restrictive, reference being had to the appended claim rather than to the foregoing description to indicate the 55 scope of the invention.

Having thus described my invention, what I claim as new, and desire to secure by Letters Patent, is:

In a vacuum cleaner, a motor, a fan chamber, a fan in said chamber actuated by said motor, a suction nozzle, a casing having a passageway therein connecting said fan chamber and said suction nozzle, valvular elements pivotally mounted within and adapted to 60 close the passageway in said casing to inter-

rupt the flow of air through said suction nozzle, and means for actuating said valvular elements comprising a solenoid, and a toggle connection operatively connecting said solenoid to said valvular elements.
